United States Patent Office

Des. 217,111
Patented Apr. 14, 1970

217,111

PINAFORE

Elsie Sutta, 4821 Hanford St.,
Douglaston, N.Y. 11362

Filed Jan. 2, 1969, Ser. No. 15,170

Term of patent 14 years

Int. Cl. D2—01

U.S. Cl. D2—81

Fig. 1.

Fig. 2.

Fig. 3.

FIG. 1 is a front elevational view of a pinafore, showing my new design;

FIG. 2 is a plan view thereof laid in a flat position; and

FIG. 3 is a front perspective view thereof, the broken background line outline of a child being for purposes of illustration only.

I claim:

The ornamental design for a pinafore, substantially as shown and described.
